UNITED STATES PATENT OFFICE.

SIGURD E. ANDERSON, OF DES MOINES, IOWA.

TRUSS OR BRIDGE FOR HOOPS OF SILOS.

Specification of Letters Patent.

Patented July 14, 1914.

1,103,339.

Application filed October 18, 1913. Serial No. 795,908.

To all whom it may concern:

Be it known that I, SIGURD E. ANDERSON, a citizen of the United States, residing at Des Moines, in the county of Polk and State of Iowa, have invented new and useful Improvements in Trusses or Bridges for Hoops of Silos, of which the following is a specification.

The present invention relates to improvements in a truss or bridge and more particularly to a device of this character which is to be used in conjunction with the hoops of silos for supporting the same.

The invention has for its object to provide a bridge or truss of this character which will support the hoops of the silo when passing over the door-frame.

Silos of the usual construction have substantially a cylindrical contour provided with a flat portion in which the door-frame is mounted. Hoops are then placed around the silo for bracing the same and these hoops being made of stiff material, such as cables are generally reinforced at the point where they cross the door-frame and the present invention aims to provide a truss or bridge which may be readily placed across a door-frame and not interfere with the operation of the door or the removing of the ensilage from the silo and yet support the hoops at this point.

A still further object of the present invention is to provide a truss of this character which will be comparatively inexpensive in the cost of manufacture, strong, durable and efficient when in use, which may be applied to silos of various constructions, thereby rendering the same commercially desirable.

With these and other incidental objects in view, the invention consists of certain novel features of construction, the combination of parts, and the essential elements of which are set forth in the appended claim and the preferred form of embodiment of which is hereinafter specifically described with reference to the drawings which accompany and form part of the specification.

In the drawings: Figure 1 is a front elevation of a portion of the silo having the preferred form of my invention as applied thereto. Fig. 2 is a horizontal section through the same. Fig. 3 is a horizontal section through a silo embodying another form of my invention, and Fig. 4 is a detail perspective view.

Referring now to the drawings wherein I

have shown a portion of a silo of the usual knock-down frame construction which comprises a plurality of wooden staves A being connected together by the usual tongue and groove connection to form a circular structure, a pair of vertically extending staves B which lie in a line of the chord of the circle form the usual door jambs of the doorway between which are adapted to rest a plurality of doors C each carrying a latch member D.

Whereas in the foregoing, I have described portions of a silo of the knock-down frame construction it is thought that further description of the same is not necessary at the present time, as the same will be readily understood by those familiar with the art.

In Figs. 1 and 2 of the drawing, I have shown one form of my improved truss as used in conjunction with a metal door-frame for silos, which comprises a pair of vertical angle irons E which rest against the staves B forming the door jambs and a plurality of transverse channel bars F which are connected to the staves B in the usual manner. For bracing silos of this construction a plurality of circumferential hoops G encircle the silo and are connected by the usual adjustable lugs H. These hoops G are usually cables and therefore are very stiff material which when passing over the flattened face of the door-frame sag at this point and prevent the hoops from being tightened up properly. The sagging of the hoops across the doorways often results in permitting the staves A of the silo to become displaced due to their warping or contracting, thereby the silo is liable to collapse.

To prevent the sagging of the hoops across the door-frame, I have provided a bridge or truss which comprises a single piece of sheet metal 1 which is adapted to rest within the channel bars F. This bar 1 has formed therewith raised portions 2 having recesses 3 formed therein in which rest the hoops G. These recesses also provide a support for the hoops to prevent the same from becoming displaced. The extremities of the bars 1 are provided with tapered recesses 4 through which pass the hoops G which prevent the hoops from being checked at this point so that the same may be readily tightened. From the structure of the truss bar as heretofore described, it is obvious that the same may be placed

within the channel bars F thereby eliminating the use of any fastening means for holding the truss bars in place.

In Fig. 3 of the drawing I have illustrated another form of truss bar which is used in conjunction with silos which are not provided with the metal door frame as before described. In this form I have provided a metal bar 5 which rests upon the cross blocks I of the door-frame and is secured to the staves B by means of the bolts 6. Secured to the outer face of the bars 5 are a plurality of angle plates 7 having V-shaped recesses formed in the outer ends

10 thereof for the reception of the hoops G. The other arms of the angle plates 7 are riveted to the bar 5 as at 8.

In Fig. 4 of the drawing I have shown a perspective view of one of the angle plates 7 which are secured to the bars 5, but it is obvious that in silos of the concrete construction the angle plates 7 may be secured thereto by means of stud bolts anchored within the silo, thereby eliminating the use 25 of the bar 5. From this it is obvious that the opening 9 formed within one arm of the angle plate may be inserted over the stud bolts carried by the concrete silo and the opposite arm having formed therein the V-shaped notch 10 will form the truss for the 30 hoops G.

While the forms of the invention herein shown and described are admirably adapted to fulfil the objects primarily stated, it is to

be understood that it is not intended to confine the invention to the forms of the embodiments herein shown and described, for it is susceptible of embodiments in various forms all coming within the scope of the claim which follows.

I claim:

The combination of a silo of circular configuration, having a flattened door frame embodying a channel shaped member secured to extend across the door opening and having open extremities, the open side of the member being outward, a truss bar constructed of a single sheet of material bent intermediate its ends to form laterally projecting V shaped portions, spaced from each other longitudinally of the member and spaced from the respective ends of the member, the apex of the projections being outward and each projection having an open recess in the apex thereof, the extremities 55 of the bar terminating adjacent the ends of the channel member, and having inclined recesses in its extremities in alignment with the recesses in the projections, to receive the encircling hoop.

In witness whereof, I hereunto subscribe my name to this specification in the presence of two witnesses.

SIGURD E. ANDERSON.
